UNITED STATES PATENT OFFICE.

AMBROSE VINCENT KELLY, OF BROOKLYN, NEW YORK.

RECEPTACLE FOR FLAGS.

Application filed July 15, 1922. Serial No. 575,214.

To all whom it may concern:

Be it known that I, AMBROSE V. KELLY, a citizen of the United States, and a resident of the city of New York, borough of Brooklyn, in the county of Kings and State of New York, have invented a new and Improved Receptacle for Flags, of which the following is a full, clear, and exact description.

10 This invention relates to new and useful improvements in flag pole attachments, and it pertains more particularly to a receptacle adapted to receive the flag and protect it from the elements when the flag is not in use.

15 The primary object of the invention is to provide means for storing the flag when not in use, said means being constructed so as to receive the flag when the same is lowered from the raised position on the flag pole.

20 A further object of the invention is to combine with the aforementioned flag-containing means, suitable means for raising and lowering the flag.

25 With the above and other objects in view, reference is had to the accompanying drawings, in which—

30 Figure 1 is a perspective view of a flag pole with the flag-containing receptacle of the present invention in operative relation therewith;

35 Fig. 2 is a detail perspective view showing the receptacle in its open position;

40 Fig. 3 is a vertical sectional view of the receptacle showing the flag pole in elevation, and taken on the line 3—3 of Fig. 4;

45 Fig. 4 is a transverse sectional view taken on the line 4—4 of Fig. 3.

50 Referring more particularly to the drawings, the reference character 5 designates a flag-pole, and said flag-pole is suitably secured in position in any desired manner and is provided with a block 6 and the usual flag halyards 7.

55 The invention comprises a receptacle 9, and said receptacle 9 comprises a rear wall 10, hinged side walls 11 and 12, and a hinged top wall 13. The hinged side walls 11 and 12 are secured to the rear wall 10, by means of hinges 14 and 15, respectively, and the top wall 13 is hinged to the upper edge of the side wall 11, by means of a hinge 16. The side walls 11 and 12 do not extend throughout the entire length of the rear wall 10, and in order to provide a com-

pletely closed receptacle, the said rear wall 10 is provided with forwardly-extending rigid side walls 17, which are connected by a front wall 18 forming a lower receptacle 19.

Extending transversely of the lower receptacle 19, is a shaft 20, and mounted on said shaft 20, is a drum 21, which is provided intermediate of its ends with an annular flange 22 serving to divide the drum into two sections. The free end of the transverse shaft 20 is squared, as at 23, to provide for the attachment of an operating handle 24.

Mounted in the lower receptacle 19, to the rear of the shaft 20, is a shaft 25, and said shaft 25 has mounted thereon two loose pulleys 26 and 27. As best shown in Fig. 4, the halyards 7 pass around the loose pulleys 26, which form guides for said halyards, and each of the halyards is attached to one of the sections of said drum, one halyard leading to the top of its respective section and the other halyard leading to the bottom of its respective section.

The operation of the device is as follows:

The side and top walls being moved to the open position shown in Fig. 2, the operating handle 24 is turned to rotate the drum 21. In this manner the flag is carried by means of the halyards 7 to the peak as shown in Fig. 1. When it is desired to lower the flag, the operating handle 24 is moved in the opposite direction and the flag will be lowered into the receptacle, after which the side walls are closed and the top wall is also closed, the halyards 7 being engaged in slots 30 in the rear wall 10 to permit of the closing of the top wall 13, as shown in Fig. 3. The side walls 11 and 12 are provided with flanges 31, which overlap each other, and the top wall 13 is likewise provided with flanges 33, which overlap the side walls when in closed position.

By this construction, it will be apparent that the receptacle 9 will be water-proof, and that the flag when contained therein will be protected from the elements.

The receptacle is secured to the flag-pole in the present instance, by means of straps 35, which embrace the same, but it is to be understood that I do not wish to be limited to this form of securing means since the receptacle may be secured to the flag-pole support instead of the flag-pole, without departing from the spirit of the invention.

Having thus described the invention, what is claimed is:

1. A device of the character described comprising a receptacle, a rear wall projecting above said receptacle, side walls hinged to the rear wall and adapted to embrace said receptacle, and a top wall hingedly secured to one of the side walls and adapted to close said receptacle. 25
- 10 2. A device of the character described comprising a receptacle, a vertically projecting rear wall extending above said receptacle, side walls hinged to said rear wall and having their lower ends overlapping the upper edge of said receptacle, and a top wall hingedly secured to one of said side walls and adapted to maintain the side walls in closed position with relation to said receptacle. 30
- 15 3. A device of the character described comprising a receptacle, a rear wall projecting above said receptacle, said rear wall having a plurality of spaced notches in its upper edge, side walls hinged to said rear wall and adapted to embrace said receptacle, a top wall hingedly secured to one of said side walls, and flanges formed on said top wall and adapted to embrace all of the side walls except the one to which it is attached when in closed position. 35
- 20 4. A device of the character described comprising a receptacle having a rear wall projecting vertically therefrom, a pair of side walls hingedly secured to the side edges of said rear wall and of a length such that their lower ends will embrace the receptacle when the side walls are in closed position, and a top wall hinged to one of said side walls and having side flanges of a length such that they will embrace all but one of the side walls when the side walls and the hinged top wall are in closed position. 40

AMBROSE VINCENT KELLY.
